UNITED STATES PATENT OFFICE.

WILLIAM ANSELM COATES, OF CHORLTON-CUM-HARDY, AND GEORGE EDWARD GITTINS, AND DAVID REGINALD DAVIES, OF MANCHESTER, ENGLAND, ASSIGNEES, BY MESNE ASSIGNMENTS, TO WESTINGHOUSE ELECTRIC & MANUFACTURING COMPANY, A CORPORATION OF PENNSYLVANIA.

ELECTRICAL SWITCH GEAR.

1,402,570.

Specification of Letters Patent.

Patented Jan. 3, 1922.

Application filed January 20, 1921. Serial No. 438,614.

To all whom it may concern:

Be it known that we, WILLIAM ANSELM COATES, a subject of the King of Great Britain, and a resident of Chorlton-cum-Hardy, in the county of Lancaster, England, GEORGE EDWARD GITTINS, a subject of the King of Great Britain, and a resident of Stretford, Manchester, in the county of Lancaster, England, and DAVID REGINALD DAVIES, a subject of the King of Great Britain, and a resident of Stretford, Manchester, in the county of Lancaster, England, have invented a new and useful Improvement in and Relating to Electrical Switch Gears, of which the following is a specification.

This invention relates to electrical switch gear of what is commonly known as the iron-clad type and has for its object to construct improved apparatus of this kind.

According to the invention there is provided between the oil switch and the sealing box or casing containing the end of the cable to which the switch is to be connected, one or more metal casings which contain the usual isolating switches and selector switches and the series transformers or such of these devices as are necessary or provided. The terminal rods or connections from these various devices pass out from said casing through suitable insulating bushes and at these points the appropriate boxes or casings are attached in which connection is made to the cable or to the bus-bars, as the case may be, and also with the terminals of the oil switch. After all the permanent connections have been made said casing or easings containing the isolating and selector switches and series transformers are completely filled with oil and the terminal boxes attached thereto are filled with a suitable insulating material or compound. The tank of the oil switch is filled with the usual oil.

To enable the invention to be clearly understood it will now be described with reference to the accompanying drawing which illustrates by way of example a construction of switch gear in accordance with the invention as applied to a three-phase electrical system with split conductor protection. Fig. 1 is a sectional elevation of the switch gear showing the essential elements of one phase of the system. Fig. 2 is a front elevation of the switch gear partly in section,

the left-hand central portion being a section on the line II—II of Fig. 1, whilst the right-hand central portion is a section on the line III—III of Fig. 1. Fig. 3 is a plan and Fig. 4 an end view of a detail on a larger scale. Fig. 5 is an electrical diagram of the circuits through one phase of the switch gear. Figs. 6 and 7 are elevations of interlocking mechanism for the switch gear showing the parts of the mechanism in different positions, and Fig. 8 is a plan of the same.

Referring to the drawing, 1 represents the cable, which may be the incoming cable of the feeder for example, 2 represents one phase conductor of the cable, and 3 the oil switch corresponding thereto which may be of any suitable kind. 4 represents a metal casing located between the cable 1 and the oil switch 3 containing the isolating and selector switches indicated as a whole at 5, the transformer 6 for split conductor protection and the instrument or series transformer 7 or such devices as are or may be provided. The main bus-bars are indicated by the numerals 8, 9, 10 and duplicate or hospital bars by 11, 12, 13. The leads or conductors from the isolating and selector switch contacts to the cable and bus-bars pass out of the casing 4 through the insulating bushings 14 and the leads or conductors from the switch terminals and transformer devices in the casing 4 to the terminals of the oil switch 3 pass out through insulating bushings or tubes as indicated at 15. The connections between the leads or conductors in the bushings 14 and the conductors 2 and bus-bars are contained in the terminal box 16 as indicated at 17, comprising a framelike portion 17 attached to the casing 4 and a front or cover portion 18 adapted to be attached to the rear portion 17. The said box also constitutes a trifurcating box for the cable 1 (see Fig. 2). The leads or conductors passing through the tubes or bushings 15 have connections 19 with similar insulated terminal rods in the bushings 20 connected with the terminals of the oil switch, the said terminal rods and connections being arranged in a terminal box 21 constituting part of the head of the oil switch and provided with a cover 22. The various casings and boxes 4, 16 and 21 are constructed so as to fit together and are connected by means

of bolts and nuts or in any other convenient manner.

The bus-bars are located beneath the casing 4 and may be either ordinary single core lead-covered cable or may be bare conductors located (as shown) in insulating tubes 28 filled with insulating compound. The main and auxiliary or hospital bus-bars are conveniently arranged in sector-shaped casings 24, 25 symmetrically situated as shown in Fig. 1, the said casings being mounted on supporting frames 26 carried upon main pedestals 27. The connections between the leads from the selector switches 15 and the bus-bars are constituted by conductor strips 28 enclosed in the box 16 and the latter is provided integrally, as shown, with a distributing chamber 29 which is arranged beneath the casing 4 and centrally between the two casings 24 and 25. The chamber 29 rests upon the pedestal 27 and serves to support the casing 4 in the center. A frame girder 30 rests on the upper end of the bus-bar casing 25 and supports the right-hand oil switch end of the casing 4. The lower part of the box 16 is supported on the bus-bar casing 24. The connections between the leads 28 and the bus-bars comprise copper rods arranged in tubes 31 of an insulating material such for example as the substance commonly known as bakelite. Holes are made in the chamber 29, and in the casings 24, 25 through which the conducting rods and tubes 31 pass radially as shown. After the connections in the chambers or boxes 16 and 21 have been made, insulating compound is run in, completely filling these chambers.

The diagram, Fig. 5, clearly shows the circuits of one phase of the system. The casings and boxes 4, 16 and 21 are indicated in dotted lines in this Figure. The phase conductor 2, by way of example, is of the split core type, the two splits or conductors 32 and 33 of which separate in the box 16 and are connected to the terminals of the isolating switches 34 and 35. From the other terminals of the switch, the conductors 32 and 33 pass through the split conductor protection transformer 6 and the series or instrument transformer 7, terminating in separate contact blocks in the oil switch, the bridge of which connects them together. The other terminal of the latter is connected by a lead 36, 37 to the terminals of the two selector switches 38 and 39. The latter are adapted to connect the lead 37 with either the main bus-bar 8 or the auxiliary or hospital bus-bar 13 through the leads 28. 40 represents a potential transformer which is conveniently located in a casing 41 mounted upon a frame 42 supported on the box or head 21 of the oil switch 3 (see Figs. 1 and 2). The connections between the potential transformer and the phase conductors 37

preferably comprise copper conductors in insulating tubes as represented at 43 (Fig. 1). The potential transformer is filled with oil in which the potential transformer fuses are also preferably immersed.

The operating rods 44 of the isolating and selector switches pass vertically upwards between the insulating contact supports 45 of the said switches and supporting bridge plate 46 and are connectd in any convenient manner to the switch operating mechanism indicated as a whole at 47, see Fig. 1. The operating mechanisms for all the isolating and selector switches are similar, and are arranged side by side in the same axial line. 70 75 All the switches which are to be opened or closed (that is to say, six isolating and three selector switches in a three-phase system) with duplicate bus-bars and split conductor protection are arranged to be operated simultaneously by a single lever 48 or by a hand-wheel or other mechanism. 80 85

In order that the desired selector switches may be operated to connect either the main or the hospital bus-bars to the oil switches, 90 the operating rods 44 are provided with heads or enlargements 49 designed to pass through perforations 50 in an operating bar 50* which is common to all the isolating and selector switches for each phase. 95

Either of the heads 49 of the switches 38, 39 can be operatively connected with the bar 50 by means of a sliding keyplate 51 which is channelled as shown and designed to be moved along the bar 50 to engage beneath either of the said heads or enlargements 49, slots 52 being provided in the ends of the plate as clearly shown in Figs. 3. and 4. Any other means, however, may be provided for selecting the desired switch. The 105 operating rods of the isolating switches 34 and 35 are permanently connected to the bar 50. The mechanisms 47 for each phase are provided with covers 53, which together with plates 54 cover in the casings 4. 110

The operating mechanism for the oil switch 3 (Fig. 1) is indicated as a whole by the numeral 55.

The operating mechanisms of the isolating and selector switches are preferably 115 interlocked with the mechanisms for operating the oil switches in such a manner that (1) the isolating and selector switches cannot be opened unless the oil switch is open (2) it will be possible to close the oil switch if all the isolating and selector switches are open; (3) when the oil switch is closed it will not be possible to close the isolating and selector switches; and (4) it will not be possible to remove the oil switch tank 120 or the lid of the potential transformer tank or the covers 53 of the casing 4 containing the series transformer unless both the oil switch and all isolating and selector switches are open. Interlocking devices of 125 130

this nature are well known but a specific form is illustrated by way of example in Figs. 6, 7 and 8. A rod 56 is attached at one end to a lever 56* keyed on the common 5 operating shaft 57 of the isolating and selector switches 5, the other end of the rod 56 operating in guides 58 carried on the head of the oil switch 3. The rod 56 is provided with a plate 60 having a key hole 10 slot therein with a narrow portion 61 and two large portions 62. A rod 63 is attached to the solenoid plunger of the oil switch 3 and moves with the same when the oil switch is operated, the said rod 63 being 15 provided with an enlargement 64 which may pass through either of the larger portions 62 of the key hole slot in the plate 60 but not through the narrower portion 61, the latter, however, allows the rod 63 to pass. 20 Fig. 6 shows the position of the mechanism when the isolating and selector switches 5 are closed, the oil switch being also closed. It will be seen that in this position the enlargement 64 is in the right- 25 hand end 62 of the slot so that it will be impossible to open the switches 5 as the rod 56 cannot move to the right. The opening of the oil switch raises the enlargement 64 above the plate 60 out of the slot 62 and 30 permits the rod 56 to move to the right.

Figs. 7 and 8 show the mechanism in the open position of the switch, the lever 56* having been moved to the right, and the enlargement 64 being in the left-hand portion 35 62 of the slot in the plate 60. It will thus be possible to close the oil switch if all the isolating and selector switches are opened and it will be impossible to close the switches 5 when the oil switch 3 is closed. 40 The rod 56 is also provided with a plate 65 having a keyhole slot 66 therein with an enlarged portion 67. A rod 68 connected by a link 69 to a lever portion 70 of the hinged lid 71 of the potential transformer 45 casing 41, is arranged to pass through the slot 66 and is guided at 72 in the head of the oil switch. The rod 68 is provided with an enlargement 73 for engaging in the slot 66, the arrangement being such that it will 50 not be possible to open the lid of the potential transformer tank 41 unless both the oil switch and all the isolating and selector switches are opened. Interlocking mechanism between the oil switch tank, the cover 55 of the transformer casing and the oil switch, isolating and selector switches can be so readily arranged on well known principles that it is not deemed necessary to describe any specific form. 60 When all the permanent connections of the system have been made, the casings 4 and the potential transformer casing 41 are filled with oil and the potential transformer fuses are preferably immersed in 65 the oil in the casing 41. The boxes 16 and

21, the chamber 29 and the bus-bar casings 24 and 25 are preferably run in solid with insulating compound.

It will be understood that the switch gear may be modified in various constructional ways without departing from the scope of the invention. For example, the bus-bars, the boxes 16 and 21, the oil switch 3 and the potential transformer 41 may be arranged in other positions relatively to the casing 4 and to one another. Also instead of the isolating and selector switches, and the transformer devices being arranged in one casing 4, the transformer devices may be contained in a separate casing in which arrangement, whilst the casing containing the switches is filled with oil, the casing containing the transformer devices may if desired be filled with insulating compound instead of oil. In certain cases the transformer devices may be absent. When the bus-bars are not provided in duplicate, certain of the so-called selector switches are omitted and those remaining would be more properly termed isolating switches. 90 Although the invention has been referred to as relating to iron-clad switch gear and the various casings are usually made of iron, it will be understood that other metal, for instance, a non-magnetic metal, might be 95 used when dealing with heavy currents. It will also be understood that the invention is in no way restricted to three-phase systems.

We claim as our invention:—

1. Electrical switch gear for a polyphase system comprising a separate switch for each phase, a single means for actuating the said switches, a circuit breaker and means interlocking the said actuating means with 105 the circuit breaker, whereby opening movement of the said switches is precluded so long as the circuit breaker is in closed position.

2. Electrical switch gear for a polyphase 110 system comprising a separate switch for each phase, a separate housing for each switch, a single means for actuating the said switches, a circuit breaker and means for interlocking the said actuating means with 115 the circuit breaker, whereby movement of the said switches is precluded so long as the circuit breaker is in closed position.

3. Electrical switch gear for a polyphase system comprising a separate switch for 120 each phase, a separate housing for each switch having terminals projecting therefrom, and a single distributing box joining the said housings and enclosing the said terminals and containing conductors leading to 125 and from the said terminals.

4. Electrical switch gear for a polyphase system comprising a separate switch for each phase, a separate housing for each switch, and a single distributing box having 130

- openings therein adapted to be closed by the said housings when the box and housings are in assembled operative relation.
5. The combination with a switch gear having an isolating switch and a plurality of relatively movable selector switches for controlling a plurality of circuits, of a means for simultaneously actuating the isolating switch and a selected selector switch.
6. The combination with a switch gear having an isolating switch, selector switches for controlling a plurality of circuits and an operating means therefor, of a selector device for selectively connecting a selected switch to the operating means whereby the isolating switch and the selected selector switch are actuated simultaneously.
7. Switch mechanism comprising a plurality of switches arranged side-by-side and having operating rods disposed substantially in the same plane, a member for operating the switches and a selector carried thereby for rendering certain switches operative or inoperative by the member.
8. Electrical switch gear for a polyphase system comprising a separate switch for each phase, a separate housing for each switch, a single distributing box having terminals of each phase extending therefrom connected to the said switches, a separate housing for receiving the terminals of each phase and bus bars extending through the said housings and connected to the said terminals.
9. Switch gear comprising a plurality of switches, a single means for operating the switches and being relatively movable therewith, and movable means carried by the said means for rendering the latter operative or inoperative with respect to the said switches.
10. Switch gear comprising a plurality of switches having operating stems, a relatively movable bar for operating the switches having openings through which the stems project, and means carried by the bar and selectively engaging the stems for selectively rendering the bar effective for moving a selected switch.
- In testimony whereof we have hereunto subscribed our names this 22nd day of December, 1920.
